(57) **CLAIM**
I claim the ornamental design for a bird whistle, as shown and described.

DESCRIPTION

This application relates to the following Patents and Applications:

to Design U.S. Pat. No. D679,212 S, filed on May 18, 2012, entitled Toy Bird Whistle;

to U.S. Utility patent application Ser. No. 14/229,719, filed on Mar. 28, 2014, also entitled Bird Whistle.

FIG. 1 is a left side view of a bird whistle according to the new design.

FIG. 2 is a right side view of the bird whistle according to the new design.

FIG. 3 is a front view of the bird whistle according to the new design.

FIG. 4 is a rear view of the bird whistle according to the new design.

FIG. 5 is a top view of the bird whistle according to the new design.

FIG. 6 is a vertical, longitudinal sectional view of the bird whistle, taken along the line 4-4 of FIG. 3.

FIG. 7 is a left side perspective view of the bird whistle according to the new design; and,

FIG. 8 is a right side perspective view of the bird whistle according to the new design.
